US00D950887S

(12) United States Design Patent (10) Patent No.: US D950,887 S
Price (45) Date of Patent: * May 10, 2022

(54) BRASSIERE PAD

(71) Applicant: Jinnell Price, Brooklyn, NY (US)

(72) Inventor: Jinnell Price, Brooklyn, NY (US)

() Term: 15 Years

(21) Appl. No.: 29/743,313

(22) Filed: Jul. 21, 2020

(51) LOC (13) Cl. 02-01

(52) U.S. Cl.

USPC D2/705

(58) Field of Classification Search

USPC D2/702, 703, 706-710, 718-727, 731,
D2/737, 739

CLAIM

I claim the ornamental design for a brassiere pad, as shown and described.

DESCRIPTION

FIG. 1 is a front view of a brassiere pad showing the new design.

FIG. 2 is a rear view thereof.

FIG. 3 is a right side view thereof.

FIG. 4 is a left side view thereof.

FIG. 5 is a top view thereof.

FIG. 6 is a bottom view thereof; and,

FIG. 7 is a perspective view thereof.

1 Claim, 3 Drawing Sheets
